DESIGN FOR A HOUSING FOR FEED MIXER

Louis Wenger, Sabetha, Kans.

Application August 15, 1940, Serial No. 94,431

Term of patent 7 years

To all whom it may concern:

Be it known that I, Louis Wenger, a citizen of the United States, residing at Sabetha, in the county of Nemaha and State of Kansas, have invented a new, original, and ornamental Design for a Housing for Feed Mixer, of which the following is a specification, reference being had to the accompanying drawing, forming a part thereof.

Fig. 1 is a perspective view of one end and side of a housing for feed mixer, showing my new design; and

Fig. 2 is a perspective view of the reverse side and end thereof.

I claim:

The ornamental design for a housing for feed mixer, as shown.

LOUIS WENGER.
